CLAIM

The ornamental design for a massaging device, as shown and described.

DESCRIPTION

FIG. 1 is a perspective view of a massaging device, showing my new design;

FIG. 2 is a right side elevational view thereof;

FIG. 3 is a top plan view thereof; and

FIG. 4 is a front elevational view thereof;

FIG. 5 is a bottom plane view thereof.

FIG. 6 is a left side elevational view thereof;

FIG. 7 is a rear elevational view thereof;

FIG. 8 shows a front elevational view thereof illustrating the massaging device in use; and,

FIG. 9 shows another front elevational view thereof illustrating the massaging device in use.
